TRAY TABLE

Clarence D. Zierhut, Granada Hills, Calif., assignor to
The Cal-Dak Company, Los Angeles, Calif., a corporation of California

Filed Feb. 27, 1964, Ser. No. 78,807

Term of patent 14 years

(Cl. D33—14)

FIG. 1.

FIG. 2.

FIG. 3.

FIG. 4.

FIG. 5.

FIG. 1 is a perspective view of a tray table embodying my new design;

FIG. 2 is a top plan view of the design;

FIG. 3 is a front elevational view;

FIG. 4 is a side elevational view;

FIG. 5 is a sectional view of a portion of the top of the table taken on the line 6—6 shown in FIG. 2.

I claim:

The ornamental design for a tray table, as shown.
